DESIGN FOR A TWO-PIECE HAIR ORNAMENT

Jerome C. Roberts, New York, N. Y.

Application May 21, 1946, Serial No. 129,935

Term of patent 7 years

(Cl. D86—10)

To all whom it may concern:

Be it known that I, Jerome C. Roberts, a citizen of the United States of America, residing in New York city, county of New York, and State of New York, have invented a new, original, and ornamental Design for a Two-Piece Hair Ornament, of which the following is a specification, reference being had to the accompanying drawing, forming part thereof.

Fig. 1 is a plan view of a two-piece hair ornament showing my new design.

Fig. 2 is an edge view thereof.

Fig. 3 is a plan view illustrating the hair ornament in separate position.

I claim:

The ornamental design for a two-piece hair ornament, substantially as shown.

JEROME C. ROBERTS.
